P. W. BAKER

THERMALLY ACTUATED ELECTRIC SWITCH

Filed Nov. 23, 1920

Inventor.

P. W. Baker

by *P. W. Baker* Atty.

UNITED STATES PATENT OFFICE.

PERCY WILLIAM BAKER, OF LONDON, ENGLAND.

THERMALLY-ACTUATED ELECTRIC SWITCH.

Application filed November 23, 1920. Serial No. 426,042.

To all whom it may concern:

Be it known that I, PERCY WILLIAM BAKER, a citizen of the United Kingdom of Great Britain and Ireland, and resident of 5 72 Linzee Road, Hornsey, London, N. 8, England, have invented certain new and useful Improvements in a Thermally-Actuated Electric Switch, of which the following is a specification, such as will enable

10 others skilled in the art to which it appertains to make and use the same.

This invention relates to an electric switch of the kind which is thermally actuated by current passing through it and in which a 15 base carrying suitable contacts, say spring contacts, is adapted to receive a movable or removable member, which I will call the carrier, upon which the thermally actuated device is mounted. The invention mainly 20 comprises an improved form of tubular thermally actuated device and method of actuating and mounting the same.

According to my invention I proceed substantially as follows:—

25 I arrange on the carrier a tube of metal, which is wound by a fine wire adapted when current is passing through it, to heat and expand the tube and by lengthening it to make a contact which will short circuit the 30 wire winding and allow it to cool until the said tube contracts and breaks the circuit thus redirecting the current through the winding, re-expanding the tube which again contracts, the process being repeated as long 35 as sufficient current is connected from the base contacts to the terminals, preferably knife terminals, on the carrier. This fine wire is permanently connected to the knife terminals and is short circuited only when 40 the tube makes contact.

At one end of the carrier I fit a screw carrying a platinum or other suitable tip and immediately opposite I fit another tip to the end of the tube, which makes electrical 45 and mechanical contact with the other blade or terminal.

The end of the tube next the tipped screw is normally out of contact and the other end of the tube is preferably mounted on its 50 blade terminal by slotting the tube and fitting it thereover.

The screw having the tip is preferably mounted within a screwed tube soldered or otherwise fixed to the terminal at that end. 55 This tube may be twice slit or cut, one slit may be the full length of the screwed tube

and the other say half the length. The strip of metal between the slits is bent inwardly so as to provide a firm but resilient grip on the screw. 60

The carrier is of non-conducting material and shaped so as to be easily taken in the fingers and thumb for removal and replacement.

The windings on the metal tube are suitably insulated from the tube as by wrapping the tube with paper or other material. 65

An example of the invention is shown in the accompanying drawings in which—

Fig. 1 is a view of the carrier in side elevation. 70

Fig. 2 is a view of one end of the carrier and

Fig. 3 shows the other end.

Fig. 4 represents a suitable and known 75 form of contact base.

Figs. 5 and 6 show details of the adjustable contact screw and its threaded and split holder.

Referring to Figs. 1 to 6 the carrier comprises a body part *a* of earthenware or like non-conducting material. On this body part two knife contacts *b* and *c* are mounted. The contact *c* supports the thermally-actuated tube *d* which is wound by a fine wire *e* 80 the ends of which are electrically connected to the said contacts so as to establish a permanent circuit from one contact to the other. For the purpose of fixing the tube *d* on contact *c* the tube is split for say half an 85 inch on opposite sides at *x*, *x*, to make a tight fit on the blade *c* and is then soldered, but other means of mounting and fixing may be employed. 90

Within the body part of the other knife contact *b* a threaded tube *f* is fixed and receives an adjustable screw *g* having a platinum or other suitable tip *h* positioned opposite a like tip *i* on the tube *d*. A small gap is left between these tips when the tube is unexpanded but when expanded the contacts close together and a direct path from *b* to *c* or vice versa is established for the electric current. 95

The tube or holder *f* for the screw *g* is threaded and is slit at *j*, *j* and the smaller 100 strip of metal *k* between the slits is bent slightly inwardly to provide a resilient grip for the screw.

The base shown in Fig. 4 comprises an insulating block *l* and two spring clips *m* and *n* 110 with terminal screws. These receive the knife contacts *b* and *c*.

Assume the carrier to be in position on the base and the current supplied thereto, the preliminary flow will be from one contact to the other through the wire winding *e*, 5 the heat of the wire will expand the tube *d*, tips *h* and *i* will close together and the current will pass from one contact to the other by way of the tube *d*.

The wire *e* will be short circuited and 10 will cool, tube *d* will contract, the tips *h* and *i* will separate and the current will then re-pass by the wire *e*, the tube will be reheated, the tips reclosed and the process repeated as 15 long as current flows thus producing an intermittent or flickering light in any lamps in the circuit.

What I claim and desire to secure by Letters Patent is:—

1. An electric switch, comprising a body, 20 a pair of knife contacts, one secured to the body at each end thereof, a tube having one end slotted to receive one of the knife contacts and secured thereto and having a contact point on the other end, an adjustable 25 contact point carried by the other knife contact in alignment with the contact point on the tube, and a heating coil mounted on and insulated from the tube having electrical

connection with both knife contacts for heating the tube, so that the same will expand to 30 make electrical connection between the contact points when connected in a circuit.

2. An electric switch, comprising a body, a pair of knife contacts, one secured to each end of said body, a tube having one end 35 slotted to receive one knife contact and secured thereto and having a contact point on the other end thereof, a split sleeve mounted in the other knife contact and a contact member threaded in said sleeve having a 40 point in alignment with said contact point on the tube, and a heating coil mounted on said tube, insulated therefrom and having electrical connection with both knife contacts, whereby the heating will cause the 45 expansion of the tube in an electric circuit for closing the contact points to make a circuit thru the tube and vary the effect of the current in the circuit.

In witness whereof I have hereunto set my 50 hand in presence of two witnesses.

PERCY WILLIAM BAKER.

Witnesses:

TRAYTON EDWARD BRADFORD,
EDWARD GAMELE WARREN.
